(57) **CLAIM**

We claim the ornamental design for a closure, as shown and described.

DESCRIPTION

FIG. 1 is front top perspective view of an embodiment of the claimed design;

FIG. 2 is a rear top perspective view of FIG. 1;

FIG. 3 is a right side view of FIG. 1;

FIG. 4 is a left side view of FIG. 1;

FIG. 5 is a front view of FIG. 1;

FIG. 6 is a rear view of FIG. 1;

FIG. 7 is a bottom view of FIG. 1;

FIG. 8 is a top view of FIG. 1;

FIG. 9 is a cross-section view of line 9-9 in FIG. 7;

FIG. 10 is a rear bottom perspective view of FIG. 1;

FIG. 11 is front top perspective view of an embodiment of the claimed design;

FIG. 12 is a rear top perspective view of FIG. 11;

FIG. 13 is a right side view of FIG. 11;

FIG. 14 is a left side view of FIG. 11;

FIG. 15 is a front view of FIG. 11;

FIG. 16 is a rear view of FIG. 11;

FIG. 17 is a bottom view of FIG. 11;

FIG. 18 is a top view of FIG. 11;

FIG. 19 is a cross-section view of line 19-19 in FIG. 11; and,

FIG. 20 is a rear bottom perspective view of FIG. 11.

The ornamental design which is claimed is shown in solid lines in the drawings.
